JOHN J. DOSSERT AND EDWIN E. GREEVES, OF SYRACUSE, NEW YORK, ASSIGNEES TO CROUSE-HINDS COMPANY, OF SYRACUSE, NEW YORK, A CORPORATION OF NEW YORK.

WASHING MACHINE.

Application filed February 28, 1921. Serial No. 448,459.

This invention relates to washing machines, and has for its object, a particularly simple and efficient and compact actuating mechanism, and an especially simple and compact arrangement of the actuating and the other elements of the machine, a further object being to provide a wringer which can be readily mounted and demounted and placed within the cabinet of the machine, the machine, as a whole, being particularly simple in construction, economical in manufacture and highly efficient and durable in use. The invention consists in novel features and in the combinations and constructions hereinafter set forth and claimed.

In describing this invention, reference is had to the accompanying drawings in which like characters designate corresponding parts in all the views.

Figure 1 is an elevation, partly broken away, and partly in section of our washing machine.

Figure 2 is a vertical sectional view, partly in elevation of our washing machine.

Figure 3 is a plan view, partly broken away.

Figure 4 is a fragmentary elevation showing the wringer in elevated position.

Figure 5 is an enlarged sectional view through the plunger and contiguous parts of the guiding and actuating means therefor.

Figure 6 is a detail view partly broken away of the actuating mechanism viewed from the opposite side thereof from the elevation shown in Fig. 2.

Figure 7 is a sectional view taken on the plane of line 7-7, Fig. 2, showing the actuating mechanism in plan.

Figure 8 is an inverted plan view of the plunger.

Figure 9 is a detail view of one of the sections of the plunger.

Figures 10 and 11 are respectively a side elevation partly broken away and a face view of another form of plunger.

This washing machine comprises generally, a tub, a plunger mounted in the tub to reciprocate vertically therein and move about a vertical axis, and actuating mechanism mounted on the frame and connected to the plunger to consecutively and intermittently reciprocate it and move it about its vertical axis when the plunger is down.

The plunger also preferably has a partial movement as a half oscillation in a return direction, when the plunger is up off the clothes for a purpose to be hereinafter described.

The machine also comprises a wringer normally arranged within the frame and mounted to be shifted above the frame when in use.

1 designates the frame which is here shown as rectangular in plan and includes 65 corner posts 2 and a bottom or pan 3. The frame is carried on suitable wheels or casters 4.

The top of the frame is provided with a cover 5 and generally, the sides of the 70 frame are enclosed by panels or a cabinet of any suitable construction, one of the panels or sides of the cabinet being a door 5a.

6 is the tub mounted in the frame, the tub being circular in form and preferably 75 having a roughened or corrugated bottom 7 and also having the lower part of its cylindrical wall vertically corrugated as at 8. 6a is a cover for the tub. The tub has a suitable valve controlled outlet.

9 is the plunger mounted to reciprocate vertically in the tub and also to rock about a vertical axis.

This plunger comprises generally, a central tubular body 10 for telescoping on a 85 post 11 best seen in Fig. 5 rising from the bottom of the tub, and outwardly or radially extending blades 12 having vacuum cups 13 in the form of channels extending radially relatively to the body 10. The blades 12 90 agitate or slosh the water. Hence the plunger, owing to the vacuum cups or channels, has a vacuum washing action as well as a pounding and rubbing effect on the clothes.

The plunger is also provided with air ducts leading from the cups 13 to partly relieve the vacuum therein and as here illustrated these ducts 15 lead upwardly along the tubular body 10 to the upper part of the body 10 above the high water mark, and the upper ends are closed by a valve which is here illustrated as a floating ring or washer 16 around the body 10 and resting on the upper ends of the ducts 15.

The plunger may be constructed in any suitable manner but preferably it consists of four main parts, the tubular body 10, and

triplicate sections 18 which form the blades 12 and cups 13. Each section 18 as seen in Fig. 9 consists of halves of two different and adjacent cups and blades 12. When these sections are brought together complementary halves of the vacuum cups 13 and blades 12 are brought together to form three cups and blades 12. Thus the blades are of double thickness of sheet metal.

10 As seen in Figs. 10, 11 the body 19 of the plunger may widen or be formed conical at its lower end at 20 to form a concentric central vacuum cup and the radial cups 21 intersect the central cup.

15 The actuating mechanism for the plunger is mounted within a casing 22 which in turn is mounted upon the pan 3 and this casing 22 also supports on the top thereof, a bracket as a spider 23 upon which the tub is mounted.

20 The actuating mechanism for the plunger comprises motion transmitting parts extending lengthwise of the post 11, one being connected to the plunger to transmit the reciprocating movement thereto, and the other being connected to the plunger to transmit rocking movement thereto, and actuating means for effecting such movements of the motion transmitting parts.

25 30 As here illustrated, the plunger 9 is provided with a central hollow rod 24, Fig. 5 depending into the tubular hub or body 10 thereof from a head 25 at the top of the body 10; and the part within the post 11 and body 10 for transmitting a rotative or rocking movement to the plunger, comprises a rod or tube 26 extending upwardly through the post and telescoping with the rod 24, both rods being shaped so that the rod 26 turns the rod 24, and the rod 24 can slide relatively to the rod 26.

35 40 45 As here shown, these rods 24, 26 fit one within the other and are non-circular, as square, in cross section. The rod 26 is here shown as carried by a wheel as a gear 27 mounted in the bearing or socket 28 on the casing 22 beneath the tub and in line with the post 11, said rod being fixed to the hub of the gear 27. Also, preferably, a second tube 29 projects from the hub of the gear and rotatably fits the inner bore of the post 11.

50 55 60 65 The motion transmitting part for reciprocating the plunger comprises a push rod 30 extending axially through the gear 27, the telescoping rods 24 and 26. This rod 30 is also preferably a tube and has a plug 31 at its upper end pressing against the inner face of the plug or cap 25 at the top of the body 10 of the plunger 9. As here shown, an annular plug 32 is inserted in the upper end of the body 10 of the plunger 9 around the rod 24, and the cap 25 is mounted on the upper end of the plunger 10 and is secured to the plug 32 by screws 33. A suit-

able oil cup 34 is provided on the cap from whence a duct 35 leads to supply oil to the wearing surfaces between the tubes 24 and 26. The cap is also provided with a buffer 36 against which the rod 30 thrusts. Also 70 suitable air holes 37 are provided in the plunger body 10.

75 The actuating means for the motion transmitting parts 26, 30 comprises a single actuator, and means for transmitting the plurality of movements of the actuator to such parts and hence to the plunger. The actuator as here shown comprises a member 38 mounted upon a shaft 39 journaled in the casing 22 and having points or teeth 40 for 80 coacting with a pusher or lifter 41 to which the lower end of the push rod 30 is secured. During upward movement of the pusher or lifter 41, the plunger 9 is raised, and when the lifting force of the actuator 38 is discontinued, the plunger 9 moves downwardly by gravity. As here shown, the actuator 38 which is discoidal in general form is provided with a plurality of cam points or teeth 40 coacting with one or more teeth 44 on 85 the pusher or lifter 41 so that when the pusher or lifter 41 is raised a predetermined amount the teeth 40 will pass by or clear the teeth 44 of the pusher or lifter 41 and permit the plunger 9 to drop. The lifter 41 is here shown as movable along a vertical 90 guide rod 45 suitably supported within the casing 22.

95 The actuator member 38 is also provided with a peripheral cam 46 having lateral deflections 47 and dwell or straight portions 48, and the motion of this cam 46 is transferred to the plunger 9 to rock the same by suitable means of the lever 49 pivoted at 100 105 within the casing 22 at one end, and having a segment 51, Fig. 7, at its other end and followers 52 between its ends coacting with the cam 46. The segment 51 meshes with teeth of the gear 27. The greater portion of the periphery of this gear 27 is blank or 110 unprovided with teeth and engages the wall of the socket 28 on the top of the casing 22.

115 The teeth 40 of the actuator 38 and the active portions or deflections 47 and dwell portions 48 of the cam 46 are so arranged or timed that they come into action consecutively, that is, the followers 52 of the lever 49 coact with the dwell portions 48 when the teeth 40 are raising the lifter 41.

120 Buffer means is provided for preventing dropping of the plunger 9 on the bottom of the tub when no clothes are in the tub and also means is provided for holding the lifter 41 when in its lowermost position so that the plunger is off the bottom of the tub. The buffer is here shown as a lever 53 pivoted by a pin-and-slot at 54 within the casing 22 and also pivoted at 55 to the lifter 41.

125 130 This lever 53 extends along one side of the actuator 38 and is formed with a cam slot

56 in its face opposed to the actuator 38. The actuator 38 is provided with a pin or follower 57 projecting from one side thereof, which enters the cam slot 56 and rides along 5 the same during downward movement of the plunger. The lever 53 with its cam slot 56 is arranged so that its receiving end passes into the arc or orbit of the follower 57 after the teeth 40 of the actuator have cleared the 10 teeth 44 of the lifter 41 and passes through the slot during downward movement of the plunger by gravity and positively returns the lifter and acts as a timer or synchroniser between the actuator 38 and the lifter 41.

15 The means for determining the lowermost position of the lifter 38 so as to hold the plunger off the bottom of the tub in order to avoid liability of the operator dropping the plunger 9 on the bottom of the tub when 20 replacing it on the post, consists of a locking flange 58 on one side of the actuator 38 and arranged to enter the slot 56 just behind the follower or pin 57 and support the lever 53 and hence the lifter 41 until the first 25 tooth 40 of the actuator 38 engages the teeth 40 of the lifter.

30 The flange 58 or a portion thereof passes through the slot 56 of the arm 53 when the plunger or the lifter 41 is in its lowermost position and prevents the lifter 41 from assuming a position low enough to permit the plunger to strike the bottom of the tub. The flange is long enough to have some part thereof in the groove when the teeth 40 are 35 out of engagement with the lifter 41.

35 In Figure 2, the actuator 38 and flanges 58 are shown in their position occupied just after the first tooth 40 engages the lifter 41. Just prior to this time, the rear end portion 40 of the flange is in the slot 56 and, hence, supports the lever 53 and the lifter 41. The foremost tooth 40 engages the lifter 41 as the rear end of this flange 58 passes out of the slot 56 of the lever 53.

45 As best seen in Fig. 6, the slot 56 in the lever 53 is open on its side toward the actuator 38, and the groove or slot 56 is formed with an arc-shaped portion of the same curve as the flange 58, which arc-shaped portion is 50 concentric with the actuator 38 when the lifter 41 is in its lowermost position, and said slot is also formed with an angular portion at its upper end terminating in a mouth through which the pin or roller 57 enters.

55 The lever is also formed with a passage or slot 56', Figs. 6 and 7, in line with the upper end of the arc-shaped portion of the slot 56, the passage 56' being the entrance for the flange 58. The flange 58 does not pass 60 through the angular portion of the slot or groove 56, but this flange is located a sufficient distance behind the pin or roller 57, so that, when the lever 53 has been carried upwardly by the lifter 41 to its full extent 65 the pin or roller 57 is in line with the mouth of such angular portion and moves thereinto. Immediately upon the teeth 40 of the actuator 38 passing out of mesh with the teeth 44 of the lifter, the lifter drops from the position shown in dotted lines, Fig. 2, to 70 that shown in full lines, such dropping being permitted by the arc-shaped formation or widening of the upper wall of the angular portion of the slot 56, and the lifter drops to its lowermost position and away 75 from the plunger 9 in the tub. When in this lowermost position the passage 56' is in line with the locking flange 58, and the locking flange 58 passes through the passage 56' and through the arc-shaped portion of the slot 56, and thus holds the lifter from dropping far enough to permit the plunger 9 to strike the bottom of the tub after the roller 57 has passed out of the lower end of the slot 56 and also holds 80 the teeth 44 of the lifter in position to register with the teeth 40 of the actuator 38, when said teeth 40 are carried by the actuator back into lifting position. The plunger 9 is lifted only by the lifter and falls by 85 gravity, for the reason that the rod 30, Fig. 5, merely thrusts against the lower end of the rod 24 of the plunger and is moved away from the same as the lifter 41 drops when the teeth 40 of the actuator 38 is moved out 90 of mesh with the teeth 44 of the lifter, the widened part of the angular portion of the slot 56 permitting the lifter to drop relatively to the plunger in order that the plunger may conform to the depth or thickness of 100 the clothes in the tub. This plunger is comparatively heavy and it is the weight thereof and the scrubbing action that cleanses the clothes. The lifter therefore is always free to drop when the teeth 40 of the actuator 38 105 clear the teeth 44 of the lifter, and such dropping brings the arc-shaped portion of the slot 56 and the passage 56' into concentric relation with the flange 58, so that, the flange 58 can enter the arc-shaped portion 110 of the slot 56 through the passage 56' and hold the lifter high enough to prevent the plunger 9 from striking the bottom of the tub (if the tub is empty) when in its lowermost position after the roller 57 has passed 115 out of the slot 56. The flange 58 therefore, acts to keep the teeth 44 of the lifter in position to mesh with the teeth 40 of the actuator 38, and also to prevent the plunger 120 from striking the bottom of the tub, when there are no clothes in the tub, and the lifter in its lowermost position. As the passage or slot 56' and the arc-shaped portion of the slot 56 comes into concentric relation with the flange 58 after the roller or pin 57 has 125 permitted and limited the dropping of the lifter and the lever 53, the flange 58 holds the lifter in the right position, so that, its teeth will be timed or will mesh with the teeth of the actuator after the roller 57 has 130

passed out of the slot 56, and, so that, the plunger will be limited in its dropping movement by the end of the rod 30 engaging the end of the rod 24 before the plunger strikes 5 the bottom of the tub.

The actuator 38 is operated by a shaft 59 journaled in the casing 22 and having a gear 60 thereon meshing with a gear 61 on the shaft 39. The shaft 59 is also connected to 10 a suitable motor 62 here shown as through a worm wheel 63 mounted on a shaft 59 and meshing with a worm 64 on the motor shaft 65 which is journaled in the casing 22.

The worm wheel 63 may be connected to 15 and disconnected from the shaft 59 by a suitable clutch 66 slideable on the shaft 59 into and out of engagement with the clutch face on one side of the worm wheel 63. This clutch 66 is shifted by any suitable means as a rod 67 20 extending through the casing 22 and terminating in a handle 68 near the top of the frame.

The casing 22 is oil tight and hence may 25 be partly filled with oil. Thus, all wearing parts are oiled from a single source with the exception of the sliding parts within the post 11 which are oiled from an oil cup up on top of the plunger, and also with the exception of the motor bearings which are 30 provided with oil cups.

As will be understood by those skilled in the art, this arrangement by which the washing machine mechanism can be supplied with oil which will last indefinitely, is highly 35 advantageous.

69, Figs. 1 and 4 designates the wringer which is provided with a supporting bracket 70 on one end thereof. This bracket includes 40 a tubular part mounted to turn or swivel about a non-rotatable sleeve 71 which in turn telescopes with a shaft 72 rising from and journaled in a gear box 73 suitably supported by the frame. This sleeve 71 also 45 slidably fits a bearing in a bracket 74 supported by the frame between the gear box and the top of the frame.

The rolls 75 of the wringer are actuated 50 from the shaft 59 in any suitable manner as by a shaft 76 journaled at one end in a bearing in the casing 22 in alignment with the shaft 59 and at its other end in the gear box 73, the shaft 72 before mentioned, intermeshing gears 77, 78, located in the gear box 73 and mounted on the shaft 59 55 and the lower end of the shaft 72, a shaft 79 within the sleeve 71 and telescoping with the shaft 72, and gear 80 on the upper end of the shaft 79 within a gear box 81 carried by the bracket 70 and meshing on opposite 60 sides of its axis with gears 82, 83 mounted on the shaft or axle 84 of one of the rolls of the wringer.

Either one or the other of the gears 82, 65 83 may be connected to the shaft 84 by means of a clutch mechanism 85 of any well

known construction. The shaft 76 may also be operatively connected to the shaft 59 by means of a clutch mechanism 86 of any suitable construction including a shifter rod 87 extending upwardly within the frame to 70 near the top thereof.

The telescoping shafts 72, 79 are non-circular or square in cross section and the gears 78, 80 have their hubs journaled in suitable bearings formed in the gear boxes 75 73, 81 respectively.

The wringer 69 and its sleeve 71 is shiftable vertically of the shaft 72 from a position below the top of the frame into a position above the same, and as here shown, 80 the bracket 70 and the sleeve 71 slides vertically of the shaft 72, and in order to permit this movement the shaft 79 telescopes within the shaft 72.

When the wringer 69 is in its lowermost 85 position as shown in Fig. 1, the bracket 70 rests upon a bracket 74 and when in its uppermost position rests upon the upper edge of the frame at the corner thereof. In the embodiment of the invention shown in Figs. 90 1 and 4 a base plate 88 for the bracket 70 is provided at the upper end of the sleeve 71, said plate 88 being mounted to swing about the sleeve 71 and over the upper edge of the frame at the corner thereof, and thus 95 support the wringer in its position shown in Fig. 4. The plate 88 is provided with a groove formed by shoulders 89 for receiving the upper edge of the frame.

The bracket 70 has a swiveling action 100 about the sleeve 71 and is held in any angular position by means of a suitable lock here shown as a detent 90 pivoted at 91 to the bracket 70 and having a tooth 92 arranged to engage any one of a number of sockets 105 provided on the periphery of a hub 93 of the plate 88. The wringer is also provided with a suitable quick release mechanism including a lever or levers 94 which when the tension is on the rolls project upwardly, and when the wringer has been demounted or placed in its position shown in Fig. 1, project high enough above the top of the frame to prevent closing of the cover 5 unless the lever or levers 94 are moved to lie flatwise 110 and hence release the tension on the rolls.

The construction of the quick release mechanism aside from the levers 94 which project upwardly above the top of the frame to prevent closing of the cover, form 120 no part of this invention and hence description thereof is unnecessary.

The wringer is comparatively light and can be very readily lifted to its upper position, Fig. 4 or lowered to within the frame 125 into the position shown in Fig. 1, but if desired suitable means may be provided for lifting and lowering it.

In operation, upon throwing of the clutch 66 to connect the worm wheel 63 to the shaft 130

59, the actuator 38 will be operated to first lift the plunger 9 on account of the teeth 40 engaging with the teeth 44 of the lifter 41, and after the teeth 40 have cleared the teeth 44, the plunger will drop by gravity, it being controlled in its dropping by the pin or follower 57 on the actuator 38 bearing on the walls of the slot 56 of the buffer lever 53. Also, after the follower 57 has moved 10 out of the slot 56 and before the teeth 40 have engaged the teeth 44, the lifter is held elevated far enough to prevent the plunger from striking the bottom by the flange 58 which is in the cam slot 56.

15 The flange 58 while in the slot 56 of the lever 53 holds the lever 53 elevated, and hence the lifter 41 elevated high enough to prevent the plunger from striking the bottom of the tub. Otherwise, when the teeth 20 40 pass out of engagement with the teeth 44 of the lifter 41, the lifter would drop far enough to permit the plunger to strike the bottom of the tub. The flange 58 conforms in curvature to the slot 56 of the lever 53 25 and causes the lever 53 to be drawn upwardly so that its cam slot is concentric with the center of the flange 58.

During the reciprocation of the plunger, the dwell or straight portions 48 of the cam 30 46 on the actuator 38 engage the followers 52 of the segment lever 49 so that the gear 27 is idle. However, when the reciprocation of the plunger 9 is completed and the plunger is in its down or lowermost position, the 35 active or deflected portions 47 of the cam 46 engage the followers 52 of the cam lever 49 and rock this lever to oscillate the gear 27 and hence the plunger through the rods 24, 26. The deflections 47 are so arranged that 40 an oscillating movement overlaps the reciprocating movement and takes place when the plunger is up in order that the plunger when again moved downwardly will engage the clothes at a different place than before. 45 Hence, the clothes are constantly being fed around the tub.

During the oscillation of the plunger 9 the clothes are scrubbed on the corrugated bottom and sides of the tub. During reciprocation owing to the vacuum cups at the 50 bottom of the plunger, a vacuum washing action is effected, and owing to the blades 12, a sloshing action takes place during the rocking of the plunger. Hence, in this 55 washing machine, vacuum pounding, scrubbing and sloshing actions are effected.

What we claim is:

1. In a washing machine, a tub, a plunger mounted in the tub to reciprocate vertically 60 therein, and to rock about a vertical axis, and mechanism for consecutively reciprocating the plunger and rocking it about its vertical axis when the plunger is down between the reciprocations thereof, substantially as and for the purpose described.

2. In a washing machine, a tub, a plunger mounted to reciprocate vertically in the tub, and also rock about a vertical axis, the plunger having concave vacuum cup faces on its lower side opposed to the bottom of the tub, and mechanism for consecutively reciprocating the plunger and rocking it about its vertical axis when down between the reciprocations, substantially as and for the purpose specified. 75

3. In a washing machine, a tub, a plunger mounted to reciprocate vertically in the tub, and mechanism for raising the plunger and releasing the same in its upper position to permit it to move by gravity toward the bottom of the tub, and buffer means for controlling the dropping of the plunger, substantially as and for the purpose specified. 80

4. In a washing machine, a tub, a plunger mounted to reciprocate vertically in the tub, and mechanism for raising the plunger and releasing the same in its upper position to permit it to move by gravity toward the bottom of the tub, said mechanism comprising a pusher formed with a shoulder, and a 85 rotatable actuator movable about a horizontal axis and having a tooth movable under the shoulder to lift the pusher and the plunger and to clear the shoulder to release the pusher and hence the plunger and permit the plunger to drop by gravity, and buffer means cooperating with the actuator and the pusher to control the dropping of the pusher, substantially as and for the purpose set forth. 95

5. In a washing machine, a tub, a plunger mounted to reciprocate vertically in the tub, and mechanism for raising the plunger and releasing the same in its upward position to permit it to move by gravity toward the bottom of the tub, said mechanism comprising a vertically movable pusher formed with a shoulder, and a rotatable actuator movable about a horizontal axis and having a tooth movable under the shoulder to lift the pusher and the plunger and to clear the shoulder to release the pusher and permit the plunger to drop by gravity, and buffer means comprising a lever pivoted to a fixed point relatively to the actuator and the pusher, and being also pivoted to the pusher, the lever extending adjacent the actuator and also having a cam, the actuator having a follower for engaging such cam of the lever, substantially as and for the purpose described. 105 110 115

6. In a washing machine, a tub, a plunger mounted to reciprocate vertically in the tub, and mechanism for raising the plunger and releasing the same in its upward position to permit it to move by gravity toward the bottom of the tub, said mechanism comprising a vertically movable pusher formed with a shoulder, and rotatable actuator movable about a horizontal axis and having a tooth 120 125 130

- movable under the shoulder to lift the pusher and the plunger and to clear the shoulder to release the pusher and permit the plunger to drop by gravity, and buffer means comprising a lever pivoted to a fixed point relatively to the actuator and the pusher, and being also pivoted to the pusher, the lever extending adjacent the actuator and also having a cam, the actuator having a follower for engaging such cam of the lever, the cam of the lever being arranged so that the advance end thereof is arranged in the orbit of the follower when the plunger is up to receive the follower and the lower end portion of said cam being out of such orbit and movable into the same as the plunger approaches its down position, substantially as and for the purpose specified.
7. In a washing machine, a tub, a plunger mounted to reciprocate vertically in the tub, and mechanism for raising the plunger and releasing the same in its upper position to permit it to move by gravity toward the bottom of the tub, said mechanism comprising a vertically movable pusher formed with a shoulder, and an actuator movable about a horizontal axis and having a tooth movable under the shoulder to lift the pusher and the plunger and to clear the shoulder to release the plunger and permit it to drop by gravity, and buffer means comprising a lever pivoted to a fixed point relatively to the actuator and extending in a general direction radially across the actuator, and being also pivoted to the pusher, the lever having a groove, the actuator having a follower movable in the groove of the lever, the groove being arranged so that the advance end thereof is arranged in the orbit of the follower to receive the follower when the plunger is up, and the lower end portion of said groove being out of such orbit and movable into the arc as the plunger approaches its down position, substantially as and for the purpose set forth.
8. In a washing machine, a tub, a plunger mounted to reciprocate vertically therein and to rock about a vertical axis, and mechanism for consecutively reciprocating the plunger and rocking it about its vertical axis comprising a single actuator movable about an axis and provided with a plurality of cam means for effecting movements of the plunger in two directions, means for transmitting the motion of one of said cam means to reciprocate the plunger, and means for transferring the other movement to the plunger to rock the same, substantially as and for the purpose described.
9. In a washing machine, a tub, a plunger mounted to reciprocate vertically therein and to rock about a vertical axis, mechanism for consecutively reciprocating the plunger and rocking it about its vertical axis including an actuator movable about

an axis and having a radially extending tooth, a peripheral cam with lateral deflections, means for transmitting the movement of the tooth to the plunger, and means for transmitting the movement of the peripheral cam to the plunger, substantially as and for the purpose specified. 70

10. In a washing machine, a tub, a hollow post extending vertically of the tub and a wheel at its lower end below the tub in line with the post, a plunger slidable on the post to reciprocate vertically thereon, means extending lengthwise of the post connecting the wheel to the plunger, and mechanism for reciprocating the plunger and rocking the wheel comprising an actuator having a radially extending tooth and a peripheral cam having lateral deflections, a vertical lifter connected to the plunger to reciprocate the same on the post and having a tooth arranged in the path of the tooth of said member, a lever pivoted at a fixed point and having a follower coacting with the peripheral cam, the lever being provided with a segment meshing with said wheel, substantially as and for the purpose set forth. 75 80

11. A washing machine comprising a frame, a tub mounted on the frame, a vertical tubular post in the tub, a plunger slideable vertically on the post and movable about the axis thereof, a casing mounted on the frame below the tub, and having a circular socket concentric with the axis of the post, a gear mounted in the socket and having a blank peripheral surface for engaging the wall of the socket and also having a segment of its periphery formed with gear teeth, the plunger having a rod extending vertically of the post and slidably connected to the gear to be rocked thereby and slide vertically relatively thereto, and actuating mechanism supported by the casing including motion transmitting means extending axially of the gear and the post to reciprocate the plunger, and motion transmitting means coacting with the gear to oscillate the plunger, substantially as and for the purpose described. 95 100 105

12. A washing machine comprising a tub having a fixed hollow vertical post rising from its bottom, a plunger slideable lengthwise of the post and movable about the axis of the post, and actuating mechanism for reciprocating and moving the plunger about its axis including means extending lengthwise of the post within the same to reciprocate the plunger, and additional means extending lengthwise of the post and within the same to rock the plunger about its axis, substantially as and for the purpose specified. 115 120 125

13. A washing machine comprising a tub having a hollow vertical post therein rising from the bottom thereof, a plunger having a sleeve slideable and rotatable on the post, 130

- and a rod extending lengthwise of the post within the same, and actuating mechanism for reciprocating the plunger and moving the plunger about the post including a part 5 extending into the post, and telescoping with the rod to move it about its axis and a part coacting with the plunger to reciprocate it, substantially as and for the purpose set forth.
- 10 14. A washing machine comprising a tub having a fixed hollow vertical post rising from the bottom thereof, a plunger having a sleeve slidable and rotatable on the post, and a non-circular rod extending lengthwise of the post within the same and actuating mechanism for reciprocating the plunger and moving the plunger about the post including motion transmitting parts extending into the post, one of said parts 15 being non-circular and movable about an axis and telescoping with said rod to transmit a rotative motion thereto, and the other coacting with the plunger to reciprocate the same, substantially as and for the purpose 20 described.
- 15 16. A washing machine comprising a tub having a fixed hollow vertical post rising from the bottom thereof, a plunger having a sleeve slidable and rotatable on the post, and a rod extending lengthwise of the post within the same and actuating mechanism for reciprocating the plunger and moving the plunger about the post, motion transmitting parts including parts extending into the post, one of said parts 25 coacting with the rod to turn the plunger and the other being a push rod slidable lengthwise of the post and the former rod and arranged coaxially with the former rod to transmit reciprocating movement to the plunger, substantially as and for the purpose specified.
- 20 17. A washing machine comprising a tub having a fixed hollow vertical post rising from its bottom, a wheel mounted below the tub in line with the post and rotatable relatively thereto, a tube rising from the wheel and extending within the post and having a bearing on the inner wall of the post, a second tube rising from the wheel coaxially therewith and arranged within the former tube, a plunger having a central sleeve slid- 25 able on the periphery of the post, and a coaxial tubular rod depending into the post and telescoping with the inner sleeve rising from the wheel to receive rotative motion therefrom, and a push rod extending axially of the wheel and the inner tube on the wheel and the tube of the plunger telescoping therewith, substantially as and for the purpose specified.
- 25 18. A washing machine comprising a tub having a fixed hollow vertical post rising from its bottom, a plunger slidable lengthwise of the post and movable about the axis of the post and actuating mechanism for reciprocating and moving the plunger about its axis including motion transmitting parts, one extending lengthwise of the post and within the same to reciprocate the plunger and another motion transmitting part extending lengthwise of the post and within the same and connected to the plunger to move the same about its axis, and a single actuator coacting with said motion transmitting parts, substantially as and for the purpose set forth.
- 30 19. A washing machine comprising a tub having a fixed hollow vertical post rising from its bottom, a plunger slidable lengthwise of the post and movable about the axis of the post, and actuating mechanism for reciprocating and moving the plunger about its axis comprising a

In testimony whereof, we have hereunto signed our names, at Syracuse, in the county of Onondaga, and State of New York, this 28th day of January, 1921.

JOHN J. DOSSEY.
EDWIN E. GREAVES.
